SHEET FEEDING MACHINE

Louis Landaff Matthews, Westerly, R. I., assignor
to Maxson Automatic Machinery Company,
Westerly, R. I., a corporation of Rhode Island

Application April 4, 1940, Serial No. 327,860

35 Claims.

(Cl. 271—75)

The present invention relates to machines for feeding sheet material, such as paper and the like. The invention is particularly related to machines involving high speeds, like those used at paper mills for cutting webs from a roll or rolls into sheets, and feeding the sheets, by means of more or less horizontal conveyor tapes, into a lay-boy or other magazine. The sheets are fed by high-speed tapes to low-speed tapes by which they become overlapped, and it is in this overlapped condition that they arrive in the lay-boy.

It has heretofore been customary, in some machines of the above-described character, to provide long narrow stationary metal waving fingers, snapped on to rods disposed between the tapes, with the tops of the fingers slightly above the more or less horizontal line of the tapes, for the purpose of imparting a long lengthwise stiffening wave to the sheets. In this way, the paper sheets are caused to travel substantially straight lengthwise, permitting their becoming overlapped as they travel from high-speed to low-speed tapes. Without some sort of wave, or other supporting means, the head end of a heavy, soft or thin sheet will sag down in the middle, causing it to become snubbed against the tail of the previously traveling sheet during the slowing down of the latter by the slow-speed tapes. This is as true of narrow sheets constituted of very soft or limp material as of wide sheets constituted of firmer stock. On certain classes of stock, however, it is impossible, because of injury to the stock, to drag the paper over metal waving fingers of the above-described character.

An object of the invention, therefore, is to provide a new and improved machine of the above-described character according to which it shall be possible to operate even on delicate stock.

Other objects will be explained hereinafter, and will be particularly pointed out in the appended claims.

With these ends in view, a feature of the invention resides in the provision of a substantially frictionless longitudinal waving action. The desired result may be attained in many equivalent ways, all within the scope of the present invention, one such way involving the employment of soft wave-producing members, such as substantially frictionless rolls or tapes that move with the moving paper, thereby preventing damage to the paper or other stock.

The invention will now be explained more fully in connection with the accompanying drawings, in which Fig. 1 illustrates diagrammatically a

preferred embodiment thereof, in side view; Fig. 2 is a section, taken upon the line 2—2 of Fig. 3, looking in the direction of the arrows; Fig. 3 is a fragmentary detail of a portion of the mechanism shown in Fig. 1, but on a larger scale; Fig. 4 is a view of a detail upon a still larger scale; and Fig. 5 is a corresponding plan, partly in section upon the line 5—5 of Fig. 4, looking in the direction of the arrows.

10 A web 3 is illustrated as led from a roll or rolls 50 of paper or similar material between feed rolls 52 and over a stationary bed knife or cutter 4, mounted upon a cutter unit 69. The term "web," "paper," "sheet," or its equivalent, will be employed to denote either a single layer or a plurality of superposed layers of the paper or other material. A rotary cutter 54, operated by mechanism 55, cooperates with the cutter 4 to cut the traveling web into sheets 56. The invention is equally applicable to use with previously cut sheets. Owing to the feeding action of the rolls 52, aided by gravity, the sheets 56 travel at a downward incline toward high-speed conveyor tapes or belts 2, that are mounted over rolls 10 and 66. During such travel, the heads 62 of the sheets may engage a stationary inclined guide board 77, disposed between the cutter 4 and the tapes 2, or a line of sloping or inclined disposed tapes (not shown), described in a copending application, Serial No. 326,975, filed March 30, 1940. The belts or tapes 2 are disposed approximately horizontal, substantially parallel to the bed knife 4, at a level below the level at which the web is fed between the rolls 52. The belts 2 cooperate with conveyor tapes or belts 6 that are mounted under a roll 8 and around a roll 68. Pairs of co-operating belts 2 and 6 engage portions of the sheets 56 that are spaced from each other along the width dimension of the sheets, as shown in 20 Fig. 2, and advance the engaged portions of the sheets forward, in the direction of the length dimension of the sheets, to feed the sheets, at relatively high speed, to relatively low-speed tapes 72, on which, because of the reduction in speed, the sheets become overlapped. The overlapped sheets are ultimately fed, in overlapped relation, into a lay-boy (not shown). The tapes 2 and 6 are actuated by mechanism 58, acting upon the rolls 66 and 68, desirably at a speed approximately ten per cent faster than the speed of the web 3, as determined by the feed rolls 52. The mechanism 58 may be in the form of a link chain engaging sprocket wheels upon the shafts that it turns. The roll 8 is shown positioned to the left of the rolls 66 and 68, and the roll 68 is

shown raised slightly above the tapes 2 to provide a space in which the tapes 2 and 6 may bite the heads of the oncoming sheets.

A roll 7 may be employed just back of and close to the roll 68, between the cutters 4, 54 and the tapes 2. It is shown rotated at high speed, higher than the speed of the roll 68, by the mechanism 58, its lower periphery in the direction of travel of the sheet, as indicated by the arrow, to cause it to engage or take up the tail 67 of each sheet. The roll 7 pulls the tail of each sheet temporarily with greater speed than the speed with which the tapes 2 and 6 pull the body of the sheet to feed the sheet forward toward the lay-boy (not shown).

By temporarily thus pulling the tail end 67 of each sheet forward, in substantially the direction of feed of the sheet, the roll 7 unhooks the said tail end 67 from in front of the fast-traveling rotary knife 54, thus actuating it out of the path of travel of the rotary cutter 54. If the paper becomes "hooked" on the faster-moving rotary knife 54, the roll 7, running at fast speed, and deliberately forming a loop between the fast-running roll 7 and the slower-running roll 68, will unhook it. Further description of this roll 7 may be found in a copending application, Serial No. 327,107, filed April 1, 1940.

As before stated, wave-producers have sometimes been provided, positioned between the low-speed and the high-speed tapes, but these are not adapted for use with delicate papers. The wave-producers employed according to a feature of the present invention, however, are substantially frictionless.

A metal side bearing 12 slips over a channel iron 13 that goes crosswise of the machine, for support, near the roll 10. The side bearing 12 is shown held in place by a spring clip 14 at the forward end of the bearing 12. At the rear end, the side bearing 12 slips under a small metal strip 15 fastened all the way across the channel iron 13. The side bearing 12 may thus be mounted anywhere transversely of the machine, at the will of the operator. Two side bearings 12 are illustrated in Fig. 2, positioned at two points between various spaced pairs of cooperating belts or tapes 2 and 6. Fastened to the side bearing are small wheels or pulleys 16, 74 and 76, mounted on ball bearings 80, so that they may turn very freely, without substantial friction. Depending upon the nature of the paper being handled, a soft tape or rubber band 17 may be placed around the two wheels 16 and 74 to the rear of the roll 10, so as to move with the wheels, but this is not essential. A similar rubber or other soft covering 78 may be placed around the wheel 76, in front of the roll 10, and similar coverings may be placed over the wheels 16 and 74, particularly if the band 17 is not employed.

During the feeding of the sheets 56 by the belts 2 and 6, therefore, the sheets will be substantially frictionlessly engaged by the wheels 16, 74 and 76, or by the bands 17 mounted thereover, along a stationary line extending in the direction of feed, to introduce longitudinally in the sheets waves of substantial width. This stationary line extends along a considerable or substantial distance in the direction of feed, from the wheel 16 to the wheel 76, as illustrated in Figs. 1 and 3. The head 62 of each sheet 56 will be frictionlessly engaged to introduce a wave in it prior to changing the speed of the sheet and this frictionless engagement will thereafter be continued throughout the body of the sheet to

introduce the wave in successive portions of the sheet as it is continued to be fed at high speed.

The wheel 76 acts after the band 17 or the wheels 16 and 14 to extend and maintain the waving action. The engaging band 17, if employed, and the engaging portions of the wheels 16, 14 and 76, thus constituted of soft material, move easily and freely with the sheet material, without substantial friction, at the speed, and in the direction of travel, of the sheets, as soon as touched, even lightly, by the paper. It is thus possible, with this movable-top waver, to put a lengthwise wave in even very delicate papers, of the finest stock, without scratching, marring or otherwise injuring their surfaces.

Modifications will occur to persons skilled in the art, and all such are considered to fall within the spirit and scope of the invention, as defined in the appended claims.

What is claimed is:

1. A machine of the character described having, in combination, means for feeding sheet material, means for waving the material comprising two substantially frictionless wheels, a band mounted over the wheels, means whereby the band may be actuated with the material in the direction of travel of the material, and a further wheel disposed in front of the band for aiding the waving action.

2. A machine for feeding sheet material having, in combination, means for engaging portions of the material at points spaced from each other along the width dimension of the material to feed it in the direction of the length dimension of the material, and means between the spaced points disposed along a stationary line in the line of feed and extending over a substantial distance in the direction of feed for substantially frictionlessly engaging the material during the feeding of the material to wave the material longitudinally, the last-named means comprising two substantially frictionless wheels, a band mounted over the wheels, means whereby the band may be actuated with the material in the direction of travel of the material, and a further wheel disposed in front of the band for aiding the waving action.

3. A machine for feeding sheet material having, in combination, means for substantially frictionlessly engaging the material, means for engaging portions of the material at points spaced from each other along the width dimension of the material, and means for actuating the second-named engaging means in the direction of the length dimension of the material, the frictionlessly engaging means comprising a band disposed between the spaced points, the band being normally stationary during the operation of the machine but being actuatable with the material in the direction of travel of the material to introduce a wave progressively in the material longitudinally of the material during the feeding of the material.

4. A machine for feeding sheet material having, in combination, means for substantially frictionlessly engaging the material, means for engaging portions of the material at points spaced from each other along the width dimension of the material, and means for actuating the second-named engaging means in the direction of the length dimension of the material, the frictionlessly engaging means comprising two substantially frictionless wheels disposed between the spaced points along a stationary line in the line of feed, and a band mounted over the wheels,

the band being normally stationary during the operation of the machine but being actuatable with the material in the direction of travel of the material to introduce a wave progressively in the material longitudinally of the material during the feeding of the material.

5. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a substantially frictionlessly material-engaging surface spaced substantially from the spaced points and intersecting the plane with a portion of the surface disposed to one side of the plane in order substantially frictionlessly to engage the material during the feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material, without scratching, marring or otherwise injuring the material.

6. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a substantially frictionlessly material-engaging surface spaced substantially from the spaced points and intersecting the plane with a portion of the surface disposed to one side of the plane and movable with the material in the direction of travel of the material in order substantially frictionlessly to engage the material during the feeding of the material, the last-named means comprising a wheel that is normally stationary during the operation of the machine but that is easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material, without scratching, marring or otherwise injuring the material.

7. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a soft substantially frictionlessly

material-engaging surface spaced substantially from the spaced points and intersecting the plane with a portion of the surface disposed to one side of the plane and movable with the material in the direction of travel of the material in order substantially frictionlessly to engage the material during the feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material, without scratching, marring or otherwise injuring the material.

8. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a plurality of substantially frictionlessly material-engaging surfaces spaced substantially from the spaced points and from each other along the width dimension of the material and intersecting the plane with portions of the surfaces disposed to one side of the plane in order substantially frictionlessly to engage the material during the feeding of the material, the material-engaging surfaces being normally stationary but being individually and independently of each other easily and freely movable with the material, without substantial friction, at the speed, and in the direction of travel, of the material in immediate response to the substantially frictionless engagement of the respective material-engaging surfaces by the material in order progressively to introduce substantially frictionlessly a plurality of waves of substantial width in the material longitudinally of the material during the feeding of the material, without scratching, marring or otherwise injuring the material.

9. A machine for feeding sheets having, in combination, means disposed substantially in a plane for engaging portions of the sheets near the edges and at points spaced from each other along the width dimension of the sheets, means for advancing the first-named means in substantially the said plane in the direction of the length dimension of the sheets at relatively high speed to feed the sheets at relatively high speed in the said direction, means for thereafter feeding the sheets at relatively low speed, and means having a substantially frictionlessly sheet-engaging surface spaced substantially from the spaced points and intersecting the plane with a portion of the surface disposed to one side of the plane in order substantially frictionlessly to engage the sheets during the feeding of the sheets at relatively high speed, the sheet-engaging surface being normally stationary but being easily and freely movable with the sheets, without substantial friction, at the speed, and in the direction of travel, of the sheets in immediate response to the substantially frictionless engagement of the sheet-engaging surface by the sheets in order progressively to introduce substantially friction-

lessly a wave of substantial width in the sheets longitudinally of the sheets during the feeding of the sheets at relatively high speed without scratching, marring or otherwise injuring the sheets.

10. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a substantially frictionlessly material-engaging surface spaced substantially from the spaced points and intersecting the plane with a portion of the surface disposed to one side of the plane and movable with the material in the direction of travel of the material in order substantially frictionlessly to engage the material during the feeding of the material, the last-named means comprising a normally stationary wheel that is mounted on ball bearings so that it may turn easily and freely, without substantial friction, at the speed, and in the direction of the travel, of the material in immediate response to the substantially frictionless engagement of the material-engaging surface by the material in order progressively to introduce substantially frictionlessly a wave of substantial width in the material longitudinally of the material during the feeding of the material, without scratching, marring or otherwise injuring the material.

11. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a plurality of substantially frictionlessly material-engaging surfaces spaced substantially from the spaced points and from each other along the width dimension of the material and intersecting the plane with portions of the surfaces disposed to one side of the plane in order substantially frictionlessly to engage the material during the feeding of the material, the last-named means comprising a plurality of normally stationary wheels that are mounted on ball bearings so that they may individually and independently of each other turn easily and freely, without substantial friction, at the speed, and in the direction of travel, of the material in immediate response to the substantially frictionless engagement of the respective material-engaging surfaces of the material in order progressively to introduce substantially frictionlessly a plurality of waves of substantial width in the material longitudinally of the material during the feeding of the material without scratching, marring or otherwise injuring the material.

12. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, a pair of normally

stationary wheels spaced substantially from the spaced points one behind the other in the direction of travel of the material, and a band mounted over the wheels so as to intersect the plane with a portion of the band disposed to one side of the plane, the wheels being mounted on ball bearings so that they may turn easily and freely to enable the band to move with the material, without substantial friction, at the speed, and in the direction of travel, of the material in immediate response to the engagement of the band by the material in order progressively to introduce substantially frictionlessly a wave of substantial width in the material longitudinally of the material during the feeding of the material without scratching, marring or otherwise injuring the material.

13. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, a plurality of pairs of normally stationary wheels spaced substantially from the spaced points and from each other along the width dimension of the material, the wheels of each pair being disposed one behind the other in the direction of travel of the material, and a band mounted over the wheels of each pair so as to intersect the plane with a portion of each band disposed to one side of the plane, the wheels being mounted in ball bearings so that they may turn easily and freely to enable the bands to move with the material, without substantial friction, at the speed, and in the direction of travel, of the material, in immediate response to the engagement of the bands by the material in order progressively to introduce substantially frictionlessly a plurality of waves of substantial width in the material longitudinally of the material during the feeding of the material without scratching, marring or otherwise injuring the material.

14. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, means having a substantially frictionlessly material-engaging surface spaced substantially from the spaced points and intersecting the plane with a portion of the surface disposed to one side of the plane in order substantially frictionlessly to engage the material during the feeding of the material, the material-engaging surface being normally stationary but being easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, and means disposed in front of the material-engaging surface in the direction of travel of the ma-

terial for engaging the material, thereby to extend and maintain the wave in the material.

15. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, means having a substantially frictionlessly material-engaging surface spaced substantially from the spaced points and intersecting the plane with a portion of the surface disposed to one side of the plane in order substantially frictionlessly to engage the material during the feeding of the material, the material-engaging surface being normally stationary but being easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, and a substantially frictionless wheel disposed in front of the material-engaging surface in the direction of travel of the material for engaging the material, thereby to extend and maintain the wave in the material.

16. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, means having a substantially frictionlessly material-engaging surface spaced substantially from the spaced points and intersecting the plane with a portion of the surface disposed to one side of the plane and movable with the material in the direction of travel of the material in order substantially frictionlessly to engage the material during the feeding of the material, the last-named means comprising a normally stationary wheel that is easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material, and a further normally stationary wheel disposed in front of the material-engaging surface in the direction of travel of the material for engaging the material, thereby to extend and maintain the wave in the material, the further normally stationary wheel being mounted to turn easily and freely, without substantial friction, at the speed, and in the direction of travel, of the material in immediate response to its engagement by the material.

17. A machine for feeding sheet material having, in combination, means disposed substantially in a plane for engaging portions of the material near the edges and at points spaced

from each other along the width dimension of the material, means for advancing the first-named means in substantially the said plane in the direction of the length dimension of the material to feed the material in the said direction, means having a substantially frictionlessly material-engaging surface spaced substantially from the spaced points and intersecting the plane with a portion of the surface disposed to one side of the plane and movable with the material in the direction of travel of the material in order substantially frictionlessly to engage the material during the feeding of the material, the last-named means comprising a normally stationary wheel that is mounted on ball bearings so that it may turn easily and freely, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, and a further normally stationary wheel disposed in front of the material-engaging surface in the direction of travel of the material for engaging the material, thereby to extend and maintain the wave in the material, the further normally stationary wheel being mounted on ball bearings so that it may turn easily and freely without substantial friction, at the speed, and in the direction of travel, of the material in immediate response to its engagement by the material.

18. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a substantially frictionlessly material-engaging surface spaced substantially from the spaced points and intersecting the plane with a portion of the surface disposed to one side of the plane in order substantially frictionlessly to engage the material during the feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, the last-named means being adjustable in order to adjust the position of the material-engaging surface between the spaced points.

19. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the

material in the said direction, and means having a plurality of substantially frictionlessly material-engaging surfaces spaced substantially from the spaced points and from each other along the width dimension of the material and intersecting the plane with portions of the surfaces disposed to one side of the plane in order substantially frictionlessly to engage the material during the feeding of the material, the material-engaging surfaces being normally stationary but being individually and independently of each other easily and freely movable with the material, without substantial friction, at the speed, and in the direction of travel, of the material in immediate response to the substantially frictionless engagement of the respective material-engaging surfaces by the material in order progressively to introduce substantially frictionlessly a plurality of waves of substantial width in the material longitudinally of the material during the feeding of the material without scratching, marring or otherwise injuring the material, the last-named means being adjustable in order to adjust the positions of the material-engaging surfaces between the spaced points.

20. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a substantially frictionlessly material-engaging surface spaced substantially from the spaced points and intersecting the plane with a portion of the surface disposed to one side of the plane and movable with the material in the direction of travel of the material in order substantially frictionlessly to engage the material during the feeding of the material, the last-named means comprising a normally stationary wheel that is mounted on ball bearings so that it may turn easily and freely, without substantial friction, at the speed, and in the direction of the travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, the wheel being adjustable in order to adjust its position between the spaced points.

21. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a plurality of substantially frictionlessly material-engaging surfaces spaced substantially from the spaced points and from each other along the width dimension of the material and intersecting the plane with portions of the surfaces disposed to one side of the plane in order substantially frictionlessly to engage the material during the feeding of the material, the last-named means comprising a plurality of normally stationary

wheels that are mounted on ball bearings so that they may individually and independently of each other turn easily and freely, without substantial friction, at the speed, and in the direction of travel, of the material in immediate response to the substantially frictionless engagement of the respective material-engaging surfaces of the material in order progressively to introduce substantially frictionlessly a plurality of waves of substantial width in the material longitudinally of the material during the feeding of the material without scratching, marring or otherwise injuring the material, the wheels being adjustable in order to adjust their position between the spaced points.

22. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, a pair of normally stationary wheels spaced substantially from the spaced points one behind the other in the direction of travel of the material, and a band mounted over the wheels so as to intersect the plane with a portion of the band disposed to one side of the plane, the wheels being mounted on ball bearings so that they may turn easily and freely to enable the band to move with the material, without substantial friction, at the speed, and in the direction of travel, of the material in immediate response to the engagement of the band by the material in order progressively to introduce substantially frictionlessly a wave of substantial width in the material longitudinally of the material during the feeding of the material without scratching, marring or otherwise injuring the material, the pair of normally stationary wheels being adjustable in order to adjust the position of the band between the spaced points.

23. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, a plurality of pairs of normally stationary wheels spaced substantially from the spaced points and from each other along the width dimension of the material, the wheels of each pair being disposed one behind the other in the direction of travel of the material, and a band mounted over the wheels of each pair so as to intersect the plane with a portion of each band disposed to one side of the plane, the wheels being mounted in ball bearings so that they may turn easily and freely to enable the bands to move with the material, without substantial friction, at the speed, and in the direction of travel, of the material, in immediate response to the engagement of the bands by the material in order progressively to introduce substantially frictionlessly a plurality of waves of substantial width in the material longitudinally of the material during the feeding of the material without scratching, marring or otherwise injuring the material, the pairs of normally stationary wheels being adjustable in order to adjust the position of the bands between the spaced points.

24. A machine for feeding sheet material hav-

ing, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a substantially frictionlessly material-engaging surface spaced substantially from the spaced points and intersecting the plane with a portion of the surface disposed to one side of the plane in order substantially frictionlessly to engage the material during the feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, adjacently disposed points being positioned relatively close to each other in order that the material-engaging surface may be relatively close to the adjacent spaced points between which it is disposed.

25. A machine for feeding sheet material having, in combination, means disposed substantially in a plane for engaging portions of the material near the edges and at points spaced from each other along the width dimension of the material, means for advancing the first-named means in substantially the said plane in the direction of the length dimension of the material to feed the material in the said direction, and means having a plurality of substantially frictionlessly material-engaging surfaces spaced substantially from the spaced points and from each other along the width dimension of the material and intersecting the plane with portions of the surfaces disposed to one side of the plane in order substantially frictionlessly to engage the material during the feeding of the material, the material-engaging surfaces being normally stationary but being individually and independently of each other easily and freely movable with the material, without substantial friction, at the speed, and in the direction of travel, of the material in immediate response to the substantially frictionless engagement of the respective material-engaging surfaces by the material in order progressively to introduce substantially frictionlessly a plurality of waves of substantial width in the material longitudinally of the material during the feeding of the material without scratching, marring or otherwise injuring the material, adjacently disposed spaced points being positioned relatively close to each other in order that the material-engaging surfaces may be relatively close to the adjacent spaced points between which they are respectively disposed.

26. A machine for feeding sheet material having, in combination, a roll of substantially uniform diameter, a plurality of tapes mounted in a plane over the roll, means for actuating the tapes in the plane to feed sheet material, and means having a substantially frictionlessly material-engaging surface disposed near the roll between adjacently disposed tapes and intersecting the plane with a portion of the surface

disposed to one side of the plane in order substantially frictionlessly to engage the material during feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material, in order progressively to introduce substantially frictionlessly a wave of substantial width in the material longitudinally of the material during the feeding of the material without scratching, marring or otherwise injuring the material.

27. A machine for feeding sheet material having, in combination, a roll of substantially uniform diameter, a plurality of tapes mounted in a plane over the roll, means for actuating the tapes in the plane to feed sheet material, and means having a substantially frictionlessly material-engaging surface disposed near the roll between adjacently disposed tapes and intersecting the plane with a portion of the surface disposed to one side of the plane in order substantially frictionlessly to engage the material during the feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material, in order progressively to introduce substantially frictionlessly a wave of substantial width in the material longitudinally of the material during the feeding of the material without scratching, marring or otherwise injuring the material, the last-named means being adjustable in order to adjust the position of the material-engaging surface between the tapes.

28. A machine for feeding sheet material having, in combination, a roll of substantially uniform diameter, a plurality of tapes mounted in a plane over the roll, means for actuating the tapes in the plane to feed sheet material, and means having a plurality of substantially frictionlessly material-engaging surfaces disposed near the roll respectively between adjacently-disposed tapes and intersecting the plane with portions of the surfaces disposed to one side of the plane in order substantially frictionlessly to engage the material during the feeding of the material, the material-engaging surfaces being normally stationary but being individually and independently of each other easily and freely movable with the material, without substantial friction, at the speed, and in the direction of travel, of the material in immediate response to the substantially frictionless engagement of the respective material-engaging surfaces by the material in order progressively to introduce substantially frictionlessly a plurality of waves of substantial width in the material longitudinally of the material during the feeding of the material without scratching, marring or otherwise injuring the material.

29. A machine for feeding sheet material having, in combination, a roll of substantially uniform diameter, a plurality of tapes mounted in a plane over the roll, means for actuating the tapes in the plane to feed sheet material, and means having a plurality of substantially frictionlessly

material-engaging surfaces disposed near the roll respectively between adjacently-disposed tapes and intersecting the plane with portions of the surfaces disposed to one side of the plane in order substantially frictionlessly to engage the material during the feeding of the material, the material-engaging surfaces being normally stationary but being individually and independently of each other easily and freely movable with the material, without substantial friction, at the speed, and in the direction of travel, of the material in immediate response to the substantially frictionless engagement of the respective material-engaging surfaces by the material in order progressively to introduce substantially frictionlessly a plurality of waves of substantial width in the material longitudinally of the material during the feeding of the material without scratching, marring or otherwise injuring the material, the last-named means being adjustable in order to adjust the positions of the material-engaging surfaces between the tapes.

30. A machine for feeding sheet material having, in combination, a roll of substantially uniform diameter, a plurality of tapes mounted in a plane over the roll, means for actuating the tapes in the plane to feed sheet material, and means having a substantially frictionlessly material-engaging surface disposed near the roll between adjacently disposed tapes and intersecting the plane with a portion of the surface disposed to one side of the plane in order substantially frictionlessly to engage the material during the feeding of the material, the last-named means comprising a normally stationary wheel that is mounted on ball bearings so that it may turn easily and freely, without substantial friction, at the speed, and in the direction of the travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material.

31. A machine for feeding sheet material having, in combination, a roll of substantially uniform diameter, a plurality of tapes mounted in a plane over the roll, means for actuating the tapes in the plane to feed sheet material, and means having a substantially frictionlessly material-engaging surface disposed near the roll between adjacently disposed tapes and intersecting the plane with a portion of the surface disposed to one side of the plane in order substantially frictionlessly to engage the material during the feeding of the material, the last-named means comprising a normally stationary wheel that is mounted on ball bearings so that it may turn easily and freely, without substantial friction, at the speed, and in the direction of the travel, of the material in immediate response to the substantially frictionless engagement of the material-engaging surface by the material in order progressively to introduce substantially frictionlessly a wave of substantial width in the material longitudinally of the material during the feeding of the material without scratching, marring or otherwise injuring the material, the wheel being adjustable in order to adjust its position between the tapes.

32. A machine for feeding sheet material having, in combination, a roll of substantially uniform diameter, a plurality of tapes mounted in

a plane over the roll, means for actuating the tapes in the plane to feed sheet material, and means having a plurality of substantially frictionlessly material-engaging surfaces disposed near the roll respectively between adjacently disposed tapes and intersecting the plane with portions of the surfaces disposed to one side of the plane in order substantially frictionlessly to engage the material during the feeding of the material, the last-named means comprising a plurality of normally stationary wheels that are mounted on ball bearings so that they may individually and independently of each other turn easily and freely, without substantial friction, at the speed, and in the direction of travel, of the material in immediate response to the substantially frictionless engagement of the respective material-engaging surfaces of the material in order progressively to introduce substantially frictionlessly a plurality of waves of substantial width in the material longitudinally of the material during the feeding of the material without scratching, marring or otherwise injuring the material.

25. 33. A machine for feeding sheet material having, in combination, a roll of substantially uniform diameter, a plurality of tapes mounted in a plane over the roll, means for actuating the tapes in the plane to feed sheet material, and means having a plurality of substantially frictionlessly material-engaging surfaces disposed near the roll respectively between adjacently disposed tapes and intersecting the plane with portions of the surfaces disposed to one side of the plane in order substantially frictionlessly to engage the material during the feeding of the material, the last-named means comprising a plurality of normally stationary wheels that are mounted on ball bearings so that they may individually and independently of each other turn easily and freely, without substantial friction, at the speed, and in the direction of travel, of the material in immediate response to the substantially frictionless engagement of the respective material-engaging surfaces of the material in order progressively to introduce substantially frictionlessly a plurality of waves of substantial width in the material longitudinally of the material during the feeding of the material without scratching, marring or otherwise injuring the material.

30. 35. 40. 45. 50. 55. 60. 65. 70. 75. 34. A machine for feeding sheet material having, in combination, a roll of substantially uniform diameter, a plurality of tapes mounted in a plane over the roll, means for actuating the tapes in the plane to feed sheet material, means having a substantially frictionlessly material-engaging surface disposed near the roll between adjacently disposed tapes and intersecting the plane with a portion of the surface disposed to one side of the plane in order substantially frictionlessly to engage the material during the feeding of the material, the material-engaging surface being normally stationary during the operation of the machine but being easily and freely movable with the material, without substantial friction, at the speed, and in the direction of travel, of the material in immediate response to the substantially frictionless engagement of the material-engaging surface by the material, in order progressively to introduce substantially frictionlessly a wave of substantial width in the material longitudinally of the material during the feeding of the material without scratching, mar-

ring or otherwise injuring the material, and means disposed in front of the roll in the direction of travel of the material for engaging the material thereby to extend and maintain the wave in the material.

35. A machine for feeding sheet material having, in combination, a roll of substantially uniform diameter, a plurality of tapes mounted in a plane over the roll, means for actuating the tapes in the plane to feed sheet material, means having a substantially frictionlessly material-engaging surface disposed near the roll between adjacently disposed tapes and intersecting the plane with a portion of the surface disposed to one side of the plane in order substantially frictionlessly to engage the material during the feeding of the material, the material-engaging sur-

face being normally stationary but being easily and freely movable with the material, without substantial friction, at the speed, and in the direction of travel, of the material in immediate response to the substantially frictionless engagement of the material-engaging surface by the material, in order progressively to introduce substantially frictionlessly a wave of substantial width in the material longitudinally of the material during the feeding of the material without scratching, marring or otherwise injuring the material, and a substantially frictionless wheel disposed in front of the roll in the direction of travel of the material for engaging the material thereby to extend and maintain the wave in the material.

LOUIS L. MATTHEWS.
